UNITED STATES PATENT OFFICE.

FRANK N. STEVENS, OF NEW YORK, N. Y.

DESIGN FOR A SPRAYER-BODY.

SPECIFICATION forming part of Design No. 33,985, dated January 29, 1901.

Application filed November 28, 1900. Serial No. 38,058. Term of patent 7 years.

To all whom it may concern:

Be it known that I, FRANK N. STEVENS, a citizen of the United States, residing at New York city, in the county of New York and State of New York, have invented and produced a new and original Design for a Sprayer-Body, of which the following is a specification.

My invention relates to a new and original design for a sprayer-body, as illustrated in the accompanying drawings.

Figure 1 is a top plan view of the sprayer-body embodying my design. Fig. 2 is a side elevation thereof, except that the end wall 15 of the larger cylinder is broken away to show the relation of the adjacent end of the other cylinder thereto. Fig. 3 is an end view of the design shown in Fig. 1.

The leading or material feature of my design for a sprayer-body consists of two intersecting cylinders 1 and 2, the cylinder 1 be-

ing of uniform diameter from end to end and terminating in an abrupt end wall 3, intersecting the peripheral wall of the cylinder 2, as seen in Fig. 2, the tubes 4 and 5 emanating from the walls of the cylinders 1 and 2, respectively, in intersecting planes, as seen in the drawings, and the arch 6 rising from the wall of the cylinder 2 outside of the meeting ends of the tubes 4 and 5, as seen in Fig. 3.

Having thus fully described my design, what I claim as new, and desire to secure by Letters Patent, is—

The design for a sprayer-body substantially as herein shown and described.

In witness whereof I have hereunto set my hand this 15th day of August, 1900.

FRANK N. STEVENS.
